UNITED STATES PATENT OFFICE.

EDWARD ALDOM, OF BROOKLYN, NEW YORK.

BOTTLE-STOPPER.

SPECIFICATION forming part of Letters Patent No. 252,006, dated January 10, 1882.

Application filed June 1, 1881. (No model.)

To all whom it may concern:

Be it known that I, EDWARD ALDOM, of Brooklyn, in the county of Kings and State of New York, have invented certain new and useful Improvements in Bottle-Stoppers, of which the following is a specification.

This invention has reference to improvements in that class of cork stoppers for medicine, perfumery, and other bottles in which a wire or other handle is employed for conveniently opening and closing the bottles. These handles were heretofore fastened by forcing the ends of a U-shaped wire at diametrically-opposite points through the cork until they protrude at the bottom, where they are twisted together, the twisted portion being covered by sealing-wax or otherwise, so as to protect the wire against the action of acids, which forms an objectionable feature to this class of stoppers.

My invention is designed to attach a wire handle to the cork in such a manner that the bottom of the cork is kept intact, so as not to require a covering; and it consists of a stopper in connection with a loop-shaped wire handle the ends of which pass at or near the center of the top part in oblique direction through the stopper, the ends being anchored to the sides above the bottom; and in addition to the above the looped upper portion may be twisted to form a handle for the stopper.

In the accompanying drawings, Figure 1 represents a sectional side elevation of my improved stopper for medicine, perfumery, and other bottles, showing the mode of inserting the wire handle. Fig. 2 is a vertical central section of the same, showing the wire handle attached; and Fig. 3 is a side view of the stopper and handle.

Similar letters of reference indicate corresponding parts.

A in the drawings represents a stopper, of cork or other material; B, a handle, which is formed of wire or sheet metal of suitable thickness. The wire blank is first bent into the shape of a U or loop, the ends being preferably

pointed, so as to pierce the cork more easily. The ends of the loop are forced in at the top of the cork at or near the center of the same, so as to pass obliquely through the same and out at the sides, where the ends are bent in shape of hooks, which are again pressed into the cork at points below the points of exit, so that the wire is thereby securely anchored to the cork. The upper part of the wire above the top of the cork is then twisted, as shown in Fig. 2, by which the proper strain is imparted to the ends within the cork. In this manner a very reliable connection between the wire handle and cork stopper is obtained without injuring the bottom of the cork at all, so that no sealing or covering of the bottom is required. The contents of the bottle are consequently not brought in contact with the metallic handle, as the same is fully embedded into the cork above the lower portion of the same.

Having thus described my invention, I claim as new and desire to secure by Letters Patent—

1. As an improvement in bottle-stoppers, the combination, with a cork stopper, of a loop-shaped handle the ends of which pass at or near the center of the top part in an oblique direction through the cork, and then anchor to the sides of the cork, above the bottom of the same, substantially as set forth.

2. As an improvement in bottle-stoppers, the combination, with a cork or other stopper, of a loop-shaped wire handle the ends of which pass at or near the center of the top part in an oblique direction through the cork and anchor to the sides of the same, above the bottom, the upper looped portion being tightly twisted, substantially as and for the purpose set forth.

In testimony that I claim the foregoing as my invention I have signed my name, in presence of two witnesses, this 9th day of May, 1881.

EDWARD ALDOM.
